CABLE CAPSTAN CASING

Fred Einar Ahlbin, Fairfield, and William George Hembling, Milford, Conn., assignors to The Scott & Fetzer Company, Lakewood, Ohio

Filed Oct. 4, 1974, Ser. No. 512,199

Term of patent 14 years

Int. Cl. D22—05; D8—99
U.S. Cl. D8—216

FIG. 3

FIG. 5

FIG. 1

FIG. 4

FIG. 2

FIG. 1 is a top plan of a cable capstan casing embodying our new design;

FIG. 2 is a bottom view;

FIG. 3 is a side elevational view of the casing;

FIG. 4 is an elevational view of the nearest end of the casing shown in FIG. 1; and

FIG. 5 is an elevational view of the opposite end of this casing.

We claim:

The ornamental design for a cable capstan casing, as shown.
